TRUCK STANCHION

William E. Stevens, Marion, S. C.

Application October 13, 1941, Serial No. 414,843

3 Claims. (Cl. 280—145)

This invention relates to improvements in truck stanchions.

The object of the invention is to provide a truck stanchion which can be released from the cab of the truck and allowed to swing downwardly so that it does not interfere with the unloading from the side of the body of the truck.

Another object of the invention is to provide a main locking means for the stanchions and an auxiliary locking means for the main locking means, whereby the stanchions can not be accidentally released by the operation of the main locking means.

A further object of the invention is to provide a stanchion which is held in a vertical position and rigidly locked against any movement caused by the engagement of the logs or the like therewith.

A still further object of the invention is to provide a simple and effective main and auxiliary locking means having certain details of structure and combination of parts hereinafter set forth.

In the accompanying drawings,

Figure 1 is an end view of a truck body, partly broken away, showing my device applied thereto;

Figure 2 is a vertical sectional view of Figure 1;

Figure 3 is a top plan view of Figure 1;

Figure 4 is a sectional view, taken on the line 4—4 of Figure 1;

Figure 5 is a vertical sectional view, taken on the line 5—5 of Figure 1;

Figure 6 is a sectional view, taken on the line 6—6 of Figure 3.

Referring now to the drawings, 1 and 2 represent two L-shaped angle irons supported upon the body of the truck in any desired manner, and having at their ends transverse bolts 3, extending through the vertical portions 4 and 5 of the angle irons, the same being spaced apart, as clearly shown in the drawings. Mounted on the bolt 3 is the stanchion 6, which is free to rotate on the bolt and to swing downwardly at an angle, as shown in dotted lines in Figure 1 of the drawings. Extending through the vertical portions 4 and 5 of the angle irons, on the inside of the stanchion 6, is a bolt 7, which limits the inward movement of the stanchion, as clearly shown in Figures 1 and 2 of the drawings. Extending through the vertical portions 4 and 5 of the angle irons, inside of the stanchion, is a shaft 8, carrying a cam 9, which closely fits between the portions 4 and 5, and adapted, when in one position, as shown in Figure 2 of the

drawings, to engage the lower end of the stanchion 6 below the bolt 3, whereby the stanchion is held rigidly in a vertical position against the bolt 7. The shaft 8, on the outside of the vertical portion 5 of the angle iron, has rigidly secured thereon a sleeve 10, provided with two diverging arms 11 and 12. Secured to the arm 12 is an operating rod 13, which may extend or be connected to operating means in the cab of the truck. The particular means of operating the rod 13 forms no part of this invention; and, therefore, the same is not shown. Extending through the vertical portions 4 and 5 of the angle irons is a shaft 14 having a collar 15 and surrounding the shaft between the collar 15 and the vertical portion 4 of the angle iron is a spring 16, which normally holds the shaft in the position shown in Figure 3 of the drawings. The shaft 14, on the outside of the vertical portion 5, is provided with a collar 17 which limits the inward movement of the shaft. The shaft 14, beyond the collar 17, is turned laterally, as indicated at 18, and has its free end turned inwardly at 19, and passes into an opening 20 in the vertical portion 5 of the angle iron.

The shaft 14 is moved longitudinally by any desired means which may, or may not, extend to the cab of the truck. The inwardly turned end of the shaft 14 engages the arm 11 of the shaft 8, and prevents the shaft from being rotated by the rod 13. The parts being in the position shown in Figures 1 and 2 of the drawings, the stanchion is held in a vertical position. In the movement of the cam to the position shown in Figure 2 of the drawings, the cam rocks the stanchion on the bolt 3, forcing it over against the bolt 7. When it is desired to release the stanchion, the shaft 14 is moved longitudinally bringing the end 19 out beyond the arm 11 and the cam can then be moved by the rod 13 to the position shown in Figure 2 of the drawings, which allows the stanchion to swing outwardly in the position shown in dotted lines in Figure 2 of the drawings.

Having thus described my invention, what I claim is:

1. In a device of the character described, a pair of spaced apart support members, a pivot element mounted transversely of the said members, a stanchion mounted to pivot on the said pivot element so as to provide a relatively short portion inwardly of the pivot and a long body portion outwardly thereof, a shaft mounted transversely of the support members below the stanchion pivot and spaced horizontally there-

from, a round cam element fixed eccentrically on the shaft, the said cam being disposed for turning movement to bear against the short end of the stanchion to hold the body in upstanding position and to an angular position out of the path of movement of the short end of the stanchion to allow the body to swing outward, and lever means secured to one end of the cam shaft for selective operation of the cam.

2. In a device of the character described, a pair of spaced apart support members, a pivot element mounted transversely of the said members, a stanchion mounted to pivot on the said pivot element so as to provide a relatively short portion inwardly of the pivot and a long body portion outwardly thereof, a shaft mounted transversely of the support members below the stanchion pivot and spaced horizontally therefrom, a round cam element fixed eccentrically on the shaft, the said cam being disposed for turning movement to bear against the short end of the stanchion to hold the body in upstanding position and to an angular position out of the path of movement of the short end of the stanchion to allow the body to swing outward, a pair of levers secured to one end of the cam shaft and extending radially therefrom in diverging relation, an operating member pivotally connected to one of the said levers, a transversely slidible locking member having one end disposed to normally obstruct movement of one of the said levers to preclude accidental stanchion releasing movement of the cam, and a spring

pressed locking member normally disposed to ob- 30

struct movement of the other lever to preclude accidental stanchion releasing movement of the cam.

3. In a device of the character described, a pair of spaced apart support members, a pivot element mounted transversely of the said members, a stanchion mounted to pivot on the said pivot element so as to provide a relatively short portion inwardly of the pivot and a long body portion outwardly thereof, a shaft mounted transversely of the support members below the stanchion pivot and spaced horizontally therefrom, a round cam element fixed eccentrically on the shaft, the said cam being disposed for turning movement to bear against the short end of the stanchion to hold the body in upstanding position and to an angular position out of the path of movement of the short end of the stanchion to allow the body to swing outward, a pair of levers secured to one end of the cam shaft and extending radially therefrom in diverging relation, an operating member pivotally connected to one of the said levers, a transversely slidible locking member having one end disposed to normally obstruct movement of one of the said levers to preclude accidental stanchion releasing movement of the cam, and a spring

disposed to yieldingly hold the said locking member in lever obstructing position.

WILLIAM E. STEVENS.
